ATTORNEY

UNITED STATES PATENT OFFICE.

WILLIAM M. BRADSHAW, OF WILKINSBURG, PENNSYLVANIA, ASSIGNOR TO WESTINGHOUSE ELECTRIC AND MANUFACTURING COMPANY, A CORPORATION OF PENNSYLVANIA.

ELECTRICAL MEASURING INSTRUMENT.

1,290,499.

Specification of Letters Patent. Patented Jan. 7, 1919.

Application filed May 25, 1914. Serial No. 840,754.

To all whom it may concern:

Be it known that I, WILLIAM M. BRADSHAW, a citizen of the United States, and a resident of Wilkinsburg, in the county of 5 Allegheny and State of Pennsylvania, have invented a new and useful Improvement in Electrical Measuring Instruments, of which the following is a specification.

My invention relates to electrical measuring instruments and particularly to motor 10 meters:

One object of my invention is to provide means for adapting a motor meter to operate correctly on a wide range of applied 15 voltage.

Another object of my invention is to provide the magnetic circuit of a motor meter with means for deflecting a relatively large part of its main magnetic flux through its 20 armature at predetermined times.

Heretofore, performances of 25 cycle watt-hour meters of the induction type have been found rather undesirable in that the voltage curves taken thereon did not approach a 25 straight line of constant value, and the load curves for various voltages were relatively different in value. Therefore, when the applied voltage varied from the voltage for which the instrument was calibrated, the 30 registration at the different loads was incorrect.

In my invention, I provide means for deflecting a relatively large part of the flux induced by the voltage winding, through 35 the armature when predetermined voltages are impressed thereon, in order to increase the torque of the armature and overcome the damping effect on the armature at relatively high voltages.

40 In the accompanying drawings, Figure 1 is an elevational view of the magnetizable members of a watt-hour meter embodying my invention; Fig. 2 is a sectional view taken along the line II-II of Fig. 1, and 45 Figs. 3 and 4 are curves showing the results attained with my invention.

Referring to the drawings, my invention is used in connection with a laminated magnetizable core member 1 having a central 50 leg or member 2, two side members 3 which are spaced apart at one end by air gaps 4, and downwardly projecting members 5 spaced from the central member 2 by an air gap 6. A voltage winding (not shown) is

disposed around the central member 2 and 55 current windings (not shown) are disposed upon the members 5. An armature 6^a is disposed in the air gap 6 and it is rotated by a shifting field, as is understood by those versed in the art. 60

Two magnetizable members 7, severally comprising a body portion 8 and two laterally extended arms 9, are embodied in my invention. The two magnetizable members 7 are attached to opposite sides of the central member 2 by a bolt 10, and the arms 9 extend into the air gaps 4, substantially as shown in the drawings. The bolt 10 serves the double purpose of maintaining the members 7 in position and clamping together the laminations forming the magnetizable core member 1. The arms 9 of the members 7 are usually about 1/16 of an inch in length, thereby leaving air gaps 11 between the adjacent ends which prevent the members 7 from forming a complete electrical short circuit around the member 2. The shapes of the performance curves of the meter are influenced by the lengths and sizes of the arms 9, as will hereinafter 75 be described.

The dotted lines 12 that pass through the air gaps 4 indicate the normal paths of the main magnetic flux induced by the voltage winding. A relatively large part of the 80 flux will tend to crowd through the arms 9, under normal conditions, since this path is the path of least reluctance.

However, if the load is kept constant, 90 when the voltage impressed upon the voltage winding increases to such value that the arms 9 become saturated because of the increase in flux, the reluctance of the path 12 through the air gaps 4 increases and a relatively large part of the flux will traverse a 95 parallel path 13 of relatively less reluctance. Thus, the flux will fringe out into the air gap 6 in greater proportion than the increase in voltage to intercept the armature 6^a and thus increase its torque. 100

If the potential impressed upon the potential winding of an ordinary alternating-current motor-meter increases, the speed decreases because the driving torque increases in accordance with the increase in potential, 105 while the retarding torque that is produced by the potential flux increases in accordance with the square of the increase in potential,

This is seen in the solid line curve in Fig. 4 which represents the per cent. registration of a wattmeter at varying voltages and constant load when the members 7 are not used.

- 5 If the driving torque that is produced by the potential flux is relatively large with respect to the retarding torque produced thereby and can be caused to increase at a greater rate than the increase in potential, as is the 10 case in my device, the increase in the retarding torque may be overcome and a per cent. registration curve, substantially as shown by the broken lines in Fig. 4, may be obtained. Therefore, if the arms 9 are so proportioned 15 that they become saturated above predetermined voltages, relatively more flux will intercept the armature and the resulting torque, and, consequently, the speed may be caused to be substantially constant for any 20 value of voltage above the predetermined value. By increasing the length and width of the arms 9, the value of voltage at which saturation is reached is increased.

The members 7 are shown as one means 25 for increasing the speed to compensate for the increased retardation at high voltages, but it will be understood that other means may be employed for the same purpose without departing from my invention.

- 30 Since it has been shown that the voltage curve, at full load, may be made a substantially straight line of constant value, it may be shown that, for various loads, the voltage curves may be caused to have substantially 35 the same value. The curves shown in Fig. 3 of the drawings represent the per cent. registration for three different voltages, as 90, 110, and 130 volts, for different loads. The difference in value of these curves is a very 40 small percentage of their total value and, for commercial purposes, may be considered to be the same. Since it was shown, with respect to Fig. 4 of the drawings, that, should the device 7 be omitted, the per cent. 45 registration would decrease as the value of the voltage increases, it may be seen that the curves in Fig. 3 would be relatively different in value should the device 7 be omitted.

Although the present construction has 50 been found highly effective and is that which is preferred, it is obvious that modifications may be made within the spirit of the invention, and I desire to include all such modifications within the scope of the appended 55 claims.

I claim as my invention:

1. In an electrical measuring instrument, the combination with a laminated magnetizable core having a central member and 60 side members spaced from each other at one end by air gaps, of two magnetizable members respectively supported by the central member at each side thereof and having substantially parallel arms disposed in the air 65 gaps.

2. In an electrical measuring instrument, the combination with a laminated magnetizable core having a central member and side members spaced from each other at one end by air gaps, of two magnetizable members 70 having arms extending into the air gaps, and means for supporting the said magnetizable members at each side of the central member of the said magnetizable core. 75

3. In an electrical measuring instrument, the combination with a laminated magnetizable core having a central member and side members spaced from each other at one end by air gaps, of two magnetizable members 80 severally comprising a body portion and laterally extended arms disposed in the air gaps, and means for attaching said magnetizable members to the magnetizable core member. 85

4. In an electrical measuring instrument, the combination with a laminated magnetizable core having a central member and side members spaced from each other at one end by air gaps, of two magnetizable members 90 severally comprising a body portion and laterally extended arms disposed in the air gaps, and means for attaching said magnetizable members to the magnetizable core member and for clamping the laminations 95 of the said magnetizable core member securely together.

5. In an electrical measuring instrument, the combination with a magnetizable core having members spaced apart by an air 100 gap, of two magnetizable members having laterally extending arms which are disposed in the air gap, and a bolt for attaching the said magnetizable members to the said magnetizable core. 105

6. In an electrical measuring instrument, the combination with a magnetizable core having members spaced apart by an air gap, of two magnetizable members severally comprising a body portion and laterally extended arms which are disposed in the air 110 gap. 110

7. In an electrical measuring instrument, the combination with a magnetizable core having a central member and side members spaced from each other at one end by air gaps and downwardly projecting members spaced from said central and side members by an air gap, of means for deflecting a part 115 of the flux which traverses said central and side members to said air gap between said downwardly projecting members and said central member at predetermined times. 120

8. In an electrical measuring instrument, the combination with a laminated magnetizable core having a central member and side members spaced from each other at one end by air gaps, of two magnetizable members having laterally extending arms that are disposed in the air gaps for increasing 125 130

the reluctance of the path through the air gaps between the central and side members at predetermined times.

9. In an electrical measuring instrument, the combination with a magnetizable core having a central member and side members spaced from each other at one end by air gaps and downwardly extending members unspaced from the central and side members by an air gap, of means having laterally extending arms that are disposed in the air gaps between the central and side members for causing the flux that traverses the central and side members to be deflected into the air gap between the downwardly extending and the central member under predetermined conditions.
10. In an electrical measuring instru-

ment, the combination with a laminated magnetizable core having a central member and side members spaced from each other at one end by air gaps and integral with each other at their other ends, of magnetizable means having laterally extending arms that are disposed in the air gaps between the central and side members for increasing the reluctance of the air gaps under predetermined conditions.

In testimony whereof, I have hereunto subscribed my name this 18th day of May, 1914.

WILLIAM M. BRADSHAW
